UNITED STATES PATENT OFFICE.

JOHN O. GARGAN, OF BROOKLYN, NEW YORK, ASSIGNOR TO WESTERN ELECTRIC COMPANY, INCORPORATED, OF NEW YORK, N. Y., A CORPORATION OF NEW YORK.

ELECTROSTATIC CONDENSER.

Application filed August 26, 1924. Serial No. 734,194.

This invention relates to high voltage variable air condensers, for use with radio broadcasting transmitters. These condensers are generally mounted on the backs of panels, and consequently should occupy as little space as possible.

It has been the usual procedure in building these types of condensers to support the movable plates on a shaft which is journaled in bearings carried in front and rear plates, the rear plate being generally secured to the front plate by a number of connecting members outside of the movable plates, these members functioning solely as connecting members.

Since the capacity of an air condenser for a given plate separation varies directly as the area of the plates, and this area varies directly as the square of the diameter, it is apparent that the space occupied by the connecting members, added to the clearances necessarily required to clear the rotary plates, and, when mounted on the panel, to also clear adjacent apparatus, adds greatly to the area space requirements necessary to accommodate the condenser, while adding nothing to its effective capacity area. In other words, the area occupied by these outer members and the necessary clearance often exceeds the area of the individual condenser plates themselves, due to the diameter squared effect.

In all air condensers a clearance space is left between the shaft and the stationary plates, but this area does not detract greatly from the effective plate area because it is of comparatively small diameter.

In the condenser of this invention, this clearance space is utilized for a single supporting member for both the fixed and movable plates in the form of a spindle mounted on a supporting base. The rotor hub slips over this guide spindle and rotates on conical bearings at each end of the rotor.

Since all the machining operations are confined to fitting a single hub on a solid spindle by means of conical bearings which automatically act to take up play, the difficulties usually experienced in lining up bearings which are carried in separate members are entirely eliminated and there is no looseness whatever in the bearing.

Another feature of the invention is the provision of means for eliminating backlash between the pinion and gear which con-

sists in providing a pinion which, instead of being the full width of the gear, is only one-half of its width. This pinion carries on its hub a loose gear ring of the same width as the pinion. This loose ring is secured to the pinion by a strong spring which opposes rotation of the ring with respect to the pinion. By displacing the ring one or more teeth circumferentially and retaining this relationship when meshing the pinion and ring with the gear segment, the spring is put under a tension which spreads the two meshing teeth of the pinion and gear into contact with the opposite edges of the tooth slot in the gear, thus taking up all backlash.

Other features will appear from the detailed description.

Referring to the drawings,

Fig. 1 is a side elevation partially in section of the condenser of this invention.

Fig. 2 is a partial front view showing the arrangement of parts; and

Fig. 3 is an enlarged detailed view of the gear arrangement for eliminating backlash.

The preferred form of my invention shown in the drawings embodies the principal essential features of the common type of variable air condenser, comprising in general two groups of spaced metal plates in alternate relation with a variable degree of overlapping to regulate the capacitative effect.

The parallel ring members 1 and 2, electrically connected by the bar 3, carry the two opposite groups of stationary condenser plates 4 and 5, and are supported by the porcelain insulating elements 6, 7, 8 and 9 which are attached by the cap screws 10. Insulators 6 and 7 are attached to the central axis 11, comprising the rotor spindle 12 and the supporting plate 13, which is screwed to the insulating plate 14, which in turn is attached to the panel board 15 by means of the bolts 16 and spaces 17. In circuits where the movable plates are at ground potential, the condenser may be attached directly to a grounded metal plate by means of mounting bolts in plate 13, dispensing with insulating plate 14. Insulator support 18, to which the two insulators 8 and 9 are attached, is clamped against a shoulder of spindle 12 by means of the cap screw 19 through ring washer 20 and electrical terminal washer 21.

The rotor, comprising the hub 22 and the two groups of diametrically opposed condenser plates 23 and 24, is mounted on the spindle 12 and rotates between the two bearing cones 25 and 26 which fit into the beveled seat provided in both faces of the hub 22. Cone 25 is slipped over the spindle 12, making a forced fit over a shoulder abutting member 11, while cone 26 is freely slidable 10 axially but not rotatable on the spindle 12 and is held in position in its beveled seat by the coil thrust spring 27, which is recessed in a counterbore in member 18. This arrangement provides a self-adjusting positive cone thrust-bearing which eliminates both axial and radial play and the necessity of a separate brush for making electrical contact to the rotor, since the bearings are ground to fit, making a relatively large contact surface.

A spur gear 28 is integral with one face of the hub 22 and meshes with a driving pinion which consists of two halves 29 and 30 on the insulated shaft 31, to which is attached the turning knob 32 and the graduated dial 33. The shaft passes through an eye 34 on the member 11 and is held in place by the ring and pin bearing arrangement 35. Referring to Fig. 3 which shows the gearing arrangement in detail, numeral 28 designates the driven spur gear integral with the hub 22, and 29 and 30 the two halves of the driving pinion. Pinion 29 is rigidly attached to the shaft 31, while ring 30 is circumferentially movable thereon to an extent limited by the spring 36, one end of which is rigidly fastened in the shaft 31 through a diametral drill, as shown, whereas the other end of the spring is attached 40 to ring 30 by means of the pin 37 in such a manner that the spring opposes rotation of the ring with respect to the pinion. In assembling, the ring 30 is displaced one or more teeth circumferentially with respect to the pinion 29, and both the ring and the pinion are then meshed with gear 28. The spring 36 is thus put under tension, which spreads the two meshing teeth of the ring and pinion into positive contact with the 50 opposite faces of the inter-meshing spur gear tooth space, thereby taking up all backlash, and, because the effect of the spring pressure at the tooth slightly exceeds the tooth load, the gear can be driven in either 55 direction without backlash.

In assembling the condenser of my invention, the rotor, which comprises the 90° type of sector plates 23 and 24 attached to the rotor hub 22, is slipped over the rotor spindle 12, the symmetrical center lines of the respective movable and stationary plates being at an angle of 90° with each other as shown approximately in Fig. 2. The spur gear 28 on the hub 22 is meshed with 60 the driving pinion comprised of members

29 and 30 in the manner hereinbefore described, and the thrust bearing 26 with the spring 27 are slipped over the spindle 12 and into position against the corresponding beveled recess in hub 22. The insulator support comprising the members 8, 9 and 18 is positioned by two of the tap screws 10, and the washers 20 and 21 with the tap screw 19 complete the assembly. 70

It will be understood that the above described apparatus has the same principle of operation as that of similar devices well known in the art, and, as before pointed out, the present improvement resides in the mechanical structure and arrangement of its parts. Since all of the machining operations are confined to fitting a single hub on a solid spindle by means of conical bearings which automatically take up axial and radial play, the difficulties usually experienced in lining up bearings which are carried in separate members are entirely eliminated and there is no looseness whatever in the bearings. Furthermore, since the capacity of an air condenser for a given plate separation varies directly as the area of the plates, and as this area varies directly as the square of the diameter, it is evident that the space commonly occupied by external connecting members and the like, added to the clearances necessarily required to clear the rotor plates, adds greatly to the area space requirements necessary to accommodate the condenser while adding nothing to its effective capacity area. Hence, the area occupied by these outer members and the necessary clearances often exceeds the area of the individual condenser plates, due to the diameter squared effect. This condition is most pronounced on high voltage condensers 100 where large spacing is required to avoid voltage breakdowns. In the condenser of my invention the spindle plates are electrically connected to their common support and the central axial space is utilized for 110 the insertion of the single supporting member for both fixed and movable plates in the form of a spindle integral with the base, thus economizing on space requirements for a given capacity. 115

The above description and the accompanying drawings illustrate the device in its preferred form, and slight variations in the design and structure of the several parts of the apparatus may be made without departing from the spirit or scope of the invention within the appended claims. 120

What is claimed is:

1. In a variable air condenser, a supporting member, a frame mounted thereon, stationary condenser plates supported by said frame, other plates adapted to be moved in overlapping relation with the stationary plates, a spindle supported by said member and supporting the movable condenser 130

plates, and a gearing device for rotating the movable plates on said spindle and including means for eliminating backlash.

2. An electrical air condenser comprising two groups each of fixed and movable condenser plates in alternate spaced relation and having a variable degree of overlap, gearing for controlling said overlap, said gearing provided with back-lash eliminating means, a frame, said two groups of fixed plates oppositely mounted on said frame, a spindle on said frame extending between said groups, a rotor mounted on said spindle and having said two groups of movable plates oppositely mounted thereon, said rotor turnable on said spindle by said gearing, and means between said spindle and said rotor for eliminating bearing play.

3. In a variable air condenser, the combination of a frame having a central spindle, fixed condenser plates attached to said frame, a rotor turnable on said spindle between axial cone thrust bearings, condenser plates supported by said rotor and alternately disposed between said fixed condenser plates, said rotor having a variable angular displacement with respect to said fixed condenser plates, said displacement effected by spur gearing, and said gearing having back-lash eliminating means.

4. An electrical air condenser comprising a single unitary mounting for both the stationary and the movable plates consisting of a spindle integral with a frame, two groups of superimposed stationary con-

denser plates oppositely fixed to said frame, a rotor turnable on said spindle between cone bearings, said rotor having two groups of superimposed condenser plates oppositely disposed and intermeshing with and variably overlapping said stationary condenser plates, gearing for revolving said rotor, and means for eliminating back-lash in said gearing.

5. In a variable air condenser, the combination of a mounting having a central spindle, a series of superimposed spaced stationary condenser plates supported from the mounting, a rotor turnable on said spindle between axial cone thrust bearings, a series of superimposed spaced condenser plates fixed to said rotor and alternately disposed between said stationary plates, said rotor having a spur gear meshing with a driving pinion, and said driving pinion having means for eliminating back-lash between the gear teeth by providing constant positive contact between both faces of each intermeshing gear tooth space.

6. In a variable air condenser, a supporting member, a frame mounted on said member, stationary plates supported by said frame, a spindle extending from said member, and a hub carrying the movable plates and adapted to slip in adjusted position on said spindle as a unit.

In witness whereof, I hereunto subscribe my name this 25th day of August, A. D. 1924.

JOHN O. GARGAN.
